E. L. JENKINS.

GIRL'S STREET COSTUME.

No. 18,287.

Patented May 1, 1888.

UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A GIRL'S STREET-COSTUME.

SPECIFICATION forming part of Design No. 18,287, dated May 1, 1868.

Application filed April 2, 1868. Serial No. 269,384. Term of patent 3½ years.

To all whom it may concern:

Be it known that I, ETTA L. JENKINS, of the city, county, and State of New York, have invented and produced a new and original Design for a Pattern of a Girl's Street-Costume; and I do hereby declare that the engraved prints accompanying this specification convey to any one accustomed to using paper patterns a clear understanding of how a garment made up by the pattern will appear.

The design shows a round basque-body, a full skirt depending from the body, a long tab on either side of the skirt reaching to the lower edge, a short tab overhanging the top of the long tab, a pointed hood exhibiting deeply-revealed side edges and a fullness at the neck, a narrow plastron upon the front, a standing collar that displays its left end pointed and lapping to the right shoulder, and coat-sleeves.

What I claim as my invention, and desire to secure by Letters Patent, is—

The design for a girl's street-costume, as shown in the engraved prints accompanying this specification.
